UNITED STATES PATENT OFFICE

WALTER H. HINSCH, OF CHICAGO, ILLINOIS, ASSIGNOR TO LOCOMOTIVE FIREBOX COMPANY, OF CHICAGO, ILLINOIS, A CORPORATION OF DELAWARE

SPARK ARRESTER

Application filed May 8, 1931. Serial No. 535,828.

This invention relates to improvements in spark arresters and it consists of the matters hereinafter described and more particularly pointed out in the appended claims.

5 The spark arresters with which my invention is more particularly concerned are those disposed in the smoke box of the locomotive and having an inlet opening at the front, with deflectors therein to deflect the incoming 10 products of combustion including live sparks and cinders, tangentially, whereby the same are caused to take on a whirling action in a circular path about the line of draft and its adjacent effective zone, so that they are broken up into particles of reduced dimensions 15 and weight which will enter the effective zone of draft and pass up and out the stack in a condition wherein they can start no wayside fires.

20 Such arresters as previously made had several inherent structural deficiencies which the present invention overcomes. Heretofore it was necessary to assemble the arrester on a platform in front of and outside the 25 open front end of the locomotive and then skid the assembled arrester into a proximate position in the smoke box. As such a structure is quite heavy, it is apparent that many difficulties arose in positioning the arrester 30 in the smoke box with respect to the associated nozzle and stack, due to the small working space left in the smoke box after the arrester had been approximately positioned.

35 Again, such arresters are subject to mechanical wear produced by the abrasive action of the whirling products of combustion with the result that parts require renewal. Such renewals of arrester parts entailed hard 40 and long work and required lay up time for the locomotives in which they are installed and this materially reduced the active service periods of such locomotives.

The main object of the invention is to provide 45 a construction which eliminates all of the objections heretofore inherent in such spark arresters and which construction may be easily assembled from its component parts in its place in the smoke box and this at a lower cost and with less labor and locomo-

tive lay up time than heretofore has been possible.

The above mentioned object of the invention as well as others, together with the many advantages thereof will more fully appear 55 as I proceed with my specification.

In the drawings:—

Fig. 1 is a longitudinal vertical sectional view through the smoke box end of a locomotive boiler embodying my improved spark 60 arrester with parts thereof shown broken away to more clearly illustrate the construction thereof.

Fig. 2 is a view in end elevation of the smoke box with the usual front end plate removed and shows the improved spark arrester in front elevation.

Fig. 3 is a horizontal sectional view as taken in the line 3—3 of Fig. 1 and shows the improved spark arrester in plan elevation with 70 parts thereof broken away.

Fig. 4 is a detail vertical sectional view on an enlarged scale taken on the line 4—4 of Fig. 3 and illustrates more particularly the manner of attaching the exhaust nozzle to 75 associated parts of the arrester bottom.

Fig. 5 is another detail vertical sectional view through a part of the improved spark arrester taken on the line 5—5 of Fig. 3.

Fig. 6 is a fragmentary detail view in 80 side elevation on an enlarged scale, illustrating a peculiar lap joint employed between the various sections of the tubular body of the arrester.

Fig. 7 is a perspective view of one of the 85 plates forming a part of the bottom of the arrester.

Referring now in detail to that embodiment of the invention illustrated in the drawings:—1 indicates the shell of a locomotive boiler, 2 indicates the smoke box shell and 3 indicates the front tube sheet in which the front ends of the fire tubes or flues 4 are secured in any suitable manner. The open front of the smoke box is closed by the usual 90 front plate and door (not shown). 5 indicates the exhaust pipe and 6 indicates the nozzle or tip therefor. 7 indicates the stack, arranged axially with the nozzle or tip and 8 indicates the sub-base for the stack and 100

with which is usually associated a petticoat pipe 9 that is flared at its bottom end. 10 indicates as a whole, the improved spark arrester which is of the centrifugal separator type, and which includes a tubular body 11 of substantially a horse shoe like outline, having an inlet opening 12 at the front thereof. The body has a closed bottom 13 and a closed top 14 of the same shape but of a smaller area and the top portion of the body is tapered inwardly to meet the same as is best shown in Figs. 1 and 5.

In the inlet opening or mouth are upright deflectors 15 and 16 respectively with one of 15 said deflectors associated with the central portion of the inlet end with the other one associated with one side of said opening. Within the casing and coacting with the inner end of the deflector 15 and the casing wall 20 respectively is a third deflector 17 as shown in dotted lines in Fig. 3.

For ease in manufacturing the arrester as well as for permitting the assembly of the same in the position it occupies in the smoke 25 box, it is made in sections. The sections in themselves are suitably flanged to not only provide tight seams between them but also to stiffen them, thus eliminating extraneous structural members for this purpose.

30 The body 11 is made up of a plurality of horizontally arcuate or curved intermediate sections 18 and two converging and straight or uncurved end sections 19-20, all of said sections including inwardly tapering, top portions 18^a-19^a and 20^a respectively. One margin of each section 18 and one margin of the section 20 along with the associated top portion of each of said sections is formed to provide an offset flange 18^b or 35 19^b that overlaps the other margin of the adjacent section, and key bolts 21 pass through these overlapped portions to secure them together in the desired relation. Each bolt receives a wedge shaped key 22 which 40 when driven through the usual opening in such a bolt, draws and locks said parts together in a good snug engagement. These bolts are all inserted in place from the inside of the arrester body and the keys are driven 45 into the bottom of the body so that assemblage is made much easier.

The bottom 13 is preferably made in right and left hand parts or halves 13^a-13^a one of which, is best shown in perspective in Fig. 55 7. Each half or part has a downwardly turned straight flange 13^b along one side and an upturned peripheral flange 13^c. The flange 13^b stops short of a semi-circular recess 13^d about which are openings 23 and in 60 both flanges are provided openings 24.

The top 14 which is made as an integral piece, has a downwardly inclined flange 14^a, the angularity of which conforms to the inclined top portions of the various body sections and centrally therein is an opening 25.

It is pointed out that the offset flanges or marginal portions of the various sections of the tubular body, stop short of the ends thereof, a distance approximating the height or width of the flange 13^c on the bottom and the flange 14^a on the top. The flange 14^a of the top is provided with openings 26 which are adapted to register with like openings in the top ends of the inclined top portions of the various sections.

In assembling the various parts, the two halves 13^a providing the bottom are first brought together with those portions thereof about the recesses 13^d engaging upon a flange 5^a on the top end of the nozzle 5. Thereafter the tip 6 is applied and a marginal flange 6^a thereon overlaps the said parts of said halves and bolts 27 are then passed through said flanges and through the openings 23 in said halves 13^a so as to secure said parts together as best shown in Fig. 4.

Thereafter key bolts 21 are passed through the registering openings 24 in the flanges 13^b and associated wedge keys 22 are applied thereto, to draw said flanges together. It is pointed out at this time that each half of the bottom is provided with a lug or bracket 28.

The various sections 18-19 and 20 of the tubular body are positioned upon the bottom 13, about the flange 13^c thereof. As the offset flanges 18^b-19^b of the various sections 18 and 20 terminate short of the bottom edges of said sections, said sections may be engaged flush with the inside of the flange 13^c and this will bring the bottom edge of the offset flange in a position wherein it just clears the flange 13^c as best shown in Fig. 6. Thereafter key bolts 21 are inserted through the openings in the bottom margins of said body sections and through the openings 24 in the flanges 13^b from the inside of the body and associated wedge keys 22 are then applied to the bolts to secure the bottom end of the body sections to the bottom. By means of the key bolts and wedges the associated parts are drawn into a snug tight engagement whereby the joints or seams are indeed quite tight.

Either after or before the assembly has thus far progressed, a foot or support 29 may be positioned between the smoke box shell and the inlet end of the bottom to support said end from the shell. Thereafter relatively long suspending or hanger bolts 30 carried by brackets 31 on the inside of the smoke box shell in line with the brackets 28 on the bottom 13 have their threaded ends extended through the brackets 28 and then nuts 32 are applied to said ends of said bolts. Thus the bottom may be leveled and secured held in position.

After the tubular body has thus far been assembled the top 14 is applied with its flange 14^a engaging the outer face of the top margins of all tapered top parts of the body sec-

tions. Before so applying the top, the petticoat 9 is placed in the body from the open top, as is the stack sub-base 8 and after the top has been thus positioned, key bolts 21 and associated wedges 22 are then employed to secure the top to the body. Thereafter the petticoat and sub-base are lifted into position and bolts 33 are then passed through the top, the bottom flange 8^a of the sub-base and 5 ears 9^a on the petticoat pipe to secure the parts in position. The stack 7 is then positioned and the sub-base is bolted to the bottom end thereof, all as best shown in Fig. 1.

A short distance rearward of the inlet opening 12 there is applied to the thus far assembled structure, a flange 34, which follows up the upright side and inclined wall part of the body and then across the top. This flange is disposed in the plane of an angle bar 35 10 on the inside of the smoke box shell and a baffle plate 36 is secured thereto by means of other key bolts 21 and wedges 22. This baffle terminates at the bottom in the plane of the top edges of the upright flanges 13^a of the 15 bottom 13.

On the top surface of the bottom 13 axially within the body is provided an upstanding ring 37 that is preferably of a diameter greater than that of the flared bottom end 30 of the petticoat pipe 9. It is convenient in the assembly of the various parts to weld this ring in place before assembling the various sections of the body upon the bottom.

In the operation of the arrester, a vacuous condition develops in the arrester casing due to nozzle action and this condition is felt throughout the smoke box and in the fire tubes that open thereinto, which induces a draft in said tubes. As the products of combustion leave the tubes to enter the smoke box, they pass downwardly and forwardly and under the baffle 36 to enter the spark arrester casing through the inlet 12 thereof. As they pass into said opening the members 15 and 16 deflect the products of combustion laterally and tangentially in a direction substantially parallel with the casing section 19 to follow about the interior of the casing whereby a whirling action is given to said products of combustion.

The heavier particles thereof whirl around the inside of the casing and not only break up into smaller particles but cool off. The action resulting is a centrifugal one so that the heavier particles tend to follow about the inside of the casing out of the zone of influence of the action of the nozzle jet, the lighter particles being crowded into said zone to pass out the stack in a cool condition and incapable of starting wayside fires.

In the movement of the heavier particles in the separator, there will be to some extent a separation between them as the centrifugal action is dissipated and some of such heavier particles will then fall to the bottom of the

casing outside the ring 37, for future removal.

Again, such particles as rise upward out of the effective action zone of the draft, will engage the inwardly tapering top portion of the casing, toward the petticoat pipe, to descend therealong and when they engage the flared end of said petticoat pipe, some of said particles are drawn into said zone to pass up the stack while others are caused to intermingle with those swirling around in the casing to be again acted upon, as before.

It is apparent that this centrifugal action of the products of combustion produces an abrasive or real mechanical wear on the upright walls of the casing to such an extent that holes may appear therein. Under such conditions, it is not necessary to remove the entire arrester to make repairs because by removing the proper key bolts, the worn section or sections can be removed from its place in the body and a new one substituted therefor. This can be done from within the smoke box. 35

By the construction described, there is a great saving not only as to material cost but also as to labor cost as the sections are all formed to pattern, ready for fitting in place in their order in the arrester. 80

While in describing the invention, I have referred in detail to the form, arrangement and construction of the various parts thereof, the same is to be considered merely as illustrative only, so that I do not wish to be limited thereto except as may be specifically set forth in the appended claims. 95 100

I claim as my invention:—

1. In combination with a locomotive smoke box shell and associated aligned smoke stack and exhaust nozzle, an upright tubular casing in said shell and enclosing portions of said stack and nozzle, said casing having converging portions at the front which define an inlet opening for the casing, a baffle closing off the space between said shell and casing excepting the bottom portion thereof and arranged to the rear of said inlet opening, and upright deflectors in said inlet opening arranged to deflect the products of combustion entering said opening into the casing in a direction substantially parallel with one of said converging portions of said casing, said casing including sections having overlapped marginal portions detachably connected together.

2. In combination with a locomotive smoke box shell and associated aligned smoke stack and exhaust nozzle, an upright tubular casing in said shell and enclosing portions of said stack and nozzle, said casing having converging portions at the front which define an inlet opening for the casing, a baffle closing off the space between said shell and casing excepting the bottom portion thereof and arranged to the rear of

said inlet opening, and upright deflectors in said inlet opening arranged to deflect the products of combustion entering said opening into the casing in a direction substantially parallel with one of said converging portions of said casing, said casing including upright sections, each having a marginal portion overlapping a marginal portion of an adjacent upright section and detachably connected thereto.

3. In combination with a locomotive smoke box shell and associated aligned smoke stack and exhaust nozzle, an upright tubular casing in said shell and enclosing portions of said stack and nozzle, said casing having converging portions at the front which define an inlet opening for the casing, a baffle closing off the space between said shell and casing excepting the bottom portion thereof and arranged to the rear of said inlet opening, and upright deflectors in said inlet opening arranged to deflect the products of combustion entering said opening into the casing in a direction substantially parallel with one of said converging portions of said casing, said casing including a bottom comprising a plurality of flanged parts detachably connected together and a plurality of upright sections, each having a portion engaged with and detachably connected to certain of the flanges of said bottom and each of said upright sections also having an upright marginal portion overlapping and detachably secured to a marginal portion of an adjacent upright section.

4. In combination with a locomotive smoke box shell and associated aligned smoke stack and exhaust nozzle, an upright tubular casing in said shell and enclosing portions of the stack and the nozzle, said casing including a flanged top, a flanged bottom, upright arcuate sections and two straight upright end sections, the latter of which converge toward each other to provide an inlet at the front of the casing, said top, bottom and upright casing sections all being detachably connected together, deflectors in said inlet operating to deflect the incoming products of combustion in a direction substantially parallel with one of said converging sections and a baffle between said shell and casing and which baffle terminates substantially in the plane of the said flanged bottom.

5. In combination with a locomotive smoke box shell and associated stack and nozzle, a casing in said shell including an upright tubular body having an inlet opening in one side, a top for said body and through which a part of said stack extends, a bottom for said body through which a part of said nozzle extends, said body comprising a plurality of sections, each offset along one margin to overlap the margin of an adjacent section, and means for securing the overlapped mar-

gins of the sections together in the desired relation.

6. In combination with a locomotive smoke box shell and associated stack and nozzle, a casing including an upright tubular body having an inlet opening in one side, a top member for said body and through which a part of said stack extends, a bottom member for said body, through which said nozzle extends, said bottom member having a marginal flange, said body comprising a plurality of sections each arranged with one of its ends in engagement with and secured to the inside of the flange of said bottom member, and each section having a margin offset to overlap the margin of an adjacent section and which offset margin terminates in the plane of the edge of said flange, means for securing said overlapped margins of said sections together and means for securing the other end of said sections to said top member.

7. In combination with a locomotive smoke box shell and associated stack and nozzle, a casing including an upright tubular body having an inlet opening in one side, a top member for said body and through which said stack extends, a bottom member for said body through which a part of said nozzle extends, said top and bottom members having marginal flanges, said body comprising a plurality of sections each arranged with its ends in engagement with and secured to the flanges of said top and bottom members and each section having a margin offset to overlap the margin of an adjacent section and which offset margins terminate in the plane of the edges of said flanges.

8. In combination with a locomotive smoke box shell and associated stack and nozzle, a casing in said shell including an upright tubular body having an inlet opening in one side and comprising a plurality of sections having upright meeting edges, a top member for said body through which a part of the stack extends, a bottom member for said body and through which a part of said nozzle extends, one of said members comprising a plurality of parts having flanges to receive and be secured to the associated ends of said sections and which parts have meeting edge flanges and means for securing the meeting edge flanges of said one of said members together.

9. In combination with a locomotive smoke box shell and associated stack and nozzle, a casing in said shell including an upright tubular body having an inlet opening in one side and comprising a plurality of sections having upright meeting edges, a top member for said body through which a part of said stack extends, said top member having a flange engaged with and secured to the top ends of said sections, and a bottom member for said body through which a part of said nozzle extends, said bottom member compris-

ing a plurality of parts having flanges to receive and be secured to the associated ends of said sections and which parts of said bottom member have meeting edge flanges and 5 means for securing said meeting edge flanges of said bottom member together.

10. In a spark arrester, a bottom therefor comprising two parts having downturned meeting edge flanges and upturned peripheral flanges, a body made up of a plurality of sections the ends of all of which are engaged with said peripheral flanges and which

sections have offset overlapping marginal flanges that terminate at the top edge of the upturned peripheral flange of the parts of said bottom, means for detachably securing said ends of said sections to said peripheral flange of said parts of said bottom and means for detachably securing said meeting edge flanges of said parts together. 70

In testimony whereof, I have hereunto set my hand, this 5th day of May, 1931. 75
